UNITED STATES PATENT OFFICE.

MERTON T. ARCHER, OF PITTSBURGH, PENNSYLVANIA, ASSIGNOR TO THE NATIONAL SUPPLY COMPANY, OF TOLEDO, OHIO, A CORPORATION OF OHIO.

WRENCH.

Application filed October 13, 1928. Serial No. 312,243.

My invention relates to wrenches designed for setting up and breaking, or disconnecting, threaded sucker rod joints, but capable of use for other purposes.

It is the practice when using a sucker rod wrench to snap up and break the sucker rod joints by a rapid movement of the wrench. Sometimes the outer end of the wrench handle is struck a blow to ensure a tight joint. It is the object of this invention to provide an improved wrench wherein the handle has a lost-motion connection with the wrench head so that the handle may acquire considerable energy in taking up the lost motion before it makes operative contact with one or more stops on the head. By this invention the handle imparts operative blows to the head either for tightening or loosening a threaded joint.

Referring to the accompanying drawings, Fig. 1 is a perspective view of my invention; Fig. 2, an end elevation of Fig. 1 looking toward the left, the handle being omitted; and Fig. 3, a section of the wrench head with the handle in side elevation and broken off, the section being taken on the line 3-3 on Fig. 2.

Referring first to Figs. 1, 2 and 3, 1 designates the wrench head having the open-end rigid U-shaped jaw 2 with a non-circular opening for the reception of articles to be turned. The head has in one edge of one leg of the jaw a rectangular opening 3 whose side walls 4 are parallel with each other and whose opposing edge walls 5 and 6 diverge from the middle thereof to the ends 7 and 8 of the head. Between the opposing points 9 and 10 where the converging walls 5 and 6 meet within the head a pivot pin 11 is passed transversely across the opening 3 and through the wrench handle 12 near one end thereof, the width of the handle transversely across the same at the center of the pivot and elsewhere in the head being preferably the same as the distance between the points 9 and 10.

The lever within the head preferably engages simultaneously upper and lower portions of walls 5 and 6 at opposite sides of the pivot, as shown in Figs. 1 and 3 and will simultaneously engage the remaining upper and lower portions of the walls 5 and 6 on opposite sides of the pivot when the lever is swung downwardly to its limit, as shown in dotted lines in Fig. 3. The edges of the handle in the head should preferably engage simultaneously an upper and lower wall of the opening 3 at each limit of its stroke to relieve the pivot of shearing strains and to distribute the shocks on the handle through the longest distance possible in the head. Strains on the pin will be lessened if the hole in the handle for the pivot is slightly larger than the pivot as shown. A close fit of the handle against the points 9 and 10 will protect the pin.

It is thus seen that the handle can deliver a heavy torque blow to the head tending to turn it one way or the other, according to the direction of motion of the handle.

I claim—

In a wrench, a head having a jaw and an opening therethrough, a handle having one end in the opening, and a pivot transversely across the opening and between the ends thereof and connecting the head and the handle, the handle having within the head two striking surfaces on each side thereof and on opposite sides of the pivot, two of said surfaces on opposite sides of the handle and on opposite sides of the pivot adapted to deliver strokes to portions of the walls of the opening on opposite sides of the pivot when the handle is swung in one direction and the remaining two of said surfaces adapted to deliver strokes to other portions of the said walls when the handle is swung in the opposite direction.

In testimony whereof I hereunto affix my signature.

MERTON T. ARCHER.
